UNITED STATES PATENT OFFICE

CHARLES E. BAILEY, OF MASCOUTAH, ILLINOIS

MIXER

Original application filed November 2, 1928, Serial No. 316,685. Divided and this application filed November 13, 1929. Serial No. 406,914.

This application is a division of an application filed by me November 2, 1928, Serial No. 316,685.

The invention provides a mixer of unique construction for combining air and any liquid fuel to produce a gaseous mixture for use in internal combustion motors, furnaces, lighting plants, and other apparatus. The invention is illustrated in the accompanying drawings and consists in certain novel features which will be hereinafter first fully described and then more particularly defined in the appended claims.

In the drawings:

15 Figure 1 is a central vertical longitudinal section of a carbureter having the invention embodied therein.

Fig. 2 is an end view of the mixer with a portion of the casing in section on the line 20 2-2 of Fig. 1, and

Fig. 3 is a top plan view of the mixer and its supporting ring.

As shown in Fig. 1, the casing is constructed in sections secured together by screws or bolts 25 inserted through confronting lugs or other projections.

The body or casing includes chambers 1, 2 and 3 and passages connecting said chambers, the chambers 1 and 2 being connected 30 by a passage 4, the chambers 1 and 3 by a passage 5, while the chambers 2 and 3 are in direct communication. An outlet 6 leads from the chamber 2 and receives a butterfly valve 7 constituting the throttle. A pipe 8 is connected with the outlet 6 to convey the gaseous mixture from the carbureter to the point of use. The air inlet 9 is in direct communication with the chamber 1. A pipe 10 connects one end of the chamber 1 with the 40 usual breather pipe, the end of the pipe having a close fit in the wall of the casing forming the side of the chamber. A rotatable valve 17 normally closes the passage 5 and is movable across the inlet 9, being connected 45 with a control element on the instrument board or otherwise conveniently positioned within reach of the operator whereby to regulate the flow from the chamber 1 into the passage 5.

50 A valve 21 within the chamber 1 controls

the flow from said chamber to the chamber 2 and is connected at one end to a lever 23.

An adjustable stop 27 mounted upon the body or casing of the carbureter engages the lever 23 and determines the normal position 55 of the valve 21.

The vaporizer 28 is located within the chamber 3, as shown, but a detailed description thereof is not necessary to an understanding of the present invention.

The mixer consists of a hollow body or shell of conical formation and of a length approximating the axial dimension of the chamber 2. The mixer is supported centrally within the chamber 2 by means of a plate 43 which is 60 clamped between the sections of the carbureter body or casing. The larger end of the mixer faces the outlet 6 and the smaller end faces the passage 4 to receive the inflowing air therefrom. In the illustrated construction, 65

the body or shell of the mixer is of thin metal which is longitudinally fluted or crimped to provide passages 44 and 45 which taper throughout their length, the smaller ends being adjacent the smaller end of the body and the larger ends coinciding with the larger end 70 of the said body or shell. The passages 44 open outwardly whereas the passages 45 open inwardly and they are closed to each other through their entire length, as shown in Figs. 70

2 and 3. A baffle 46 is located at the larger end of the mixer and serves to arrest the inflow of the air entering the mixer by way of the passage 4 and deflect the same outwardly into the air passages 45. The space surrounding 75

the mixer and formed between it and the outer wall of the chamber 2 is in communication with each of the passages 44 and with the chamber 3 to receive the gaseous mixture from the vaporizer. The passages 44 and 45 80

alternate and open into the rear end of the mixing chamber 2. The terminal portions of the walls separating the passages 44 and 45 are deflected laterally, as indicated at 47 in Figure 3, to deflect the outflowing air and 85

mixture laterally to impart a swirling movement thereto to effect a thorough mixing so that a homogeneous gas results to be supplied to the engine to obtain an explosion of maximum force. The rear wall of the chamber 2 90

is constricted on a curved line, as indicated at 48 in Figure 1, thus gradually forcing the gaseous mixture inward across the paths of the outflowing currents of air from the passages 45. This results in a thorough mixing of the air with the mixture discharging from the passages 44.

The numeral 49 designates a float chamber with which a fuel pipe (not shown) connects 10 to convey the hydrocarbon to the vaporizer, a float in the chamber 49 controlling the flow thereto in a manner well understood in the art.

When starting the engine, the valve 17 is 15 partly open and the valve 21 is closed. After the engine has warmed up sufficiently to run free the valve 21 is opened to admit additional air. The speed of the engine is controlled by means of the throttle 7 in a manner well understood. The throttle may be opened to a certain extent without moving the valve 21 and beyond the given point the valves 7 and 21 move together. The inlet 9, outlet 6, chambers 1 and 2 and the passage 4 20 are in line, as shown clearly in Figure 1 of the drawings. The chamber 3 and passage 5 are located below the chambers 1 and 2, thereby admitting of the vaporizer and float chamber occupying a position below a straight line 25 connecting the inlet 9 and outlet 6.

When the engine is running, air is drawn into the crank case through the breather pipe and air and oily vapor are drawn from the crank case and supplied to the carburetor. 30 The pressure within the crank case is not increased and there is a constant flow of air therethrough to cool the interior and carry off the oily vapor.

The stop 27 may be adjusted to properly 35 limit the throw of the lever 23 and prevent its overthrow when the throttle 7 is operated by a quick movement or jerk of the throttle lever through wear and looseness of turn-buckle joints and lever connections and which 40 would result in opening the valve 21 too far.

The throttle valve 7 and valve 21 are adjusted so that the throttle valve 7 is slightly open for idle running of engine. The valve 21 then laps over port or passage 4. A further movement of the throttle valve 7 of one-sixteenth of an inch then valve 21 commences 45 to open but at a greater rate of speed than the throttle valve 7. When the throttle valve 7 has uncovered one-half of the bore of outlet 6, valve 21 is wide open and lever 23 is against stop 27 or valve 21 is wide open when throttle valve 7 is half open.

The exhaust gases are carried through a pipe (not shown) to the vaporizer to heat the 50 same and then pass off through the pipe 42.

Having thus described the invention, I 55 claim:

1. The combination of a mixing chamber having an outlet at one end, an inlet for air 60 at the opposite end and an inlet for vapor in

one side, and a mixer comprising a hollow open-ended body having longitudinally disposed passages in its sides closed to each other through their entire length, some of the passages having open inner sides and the alternate passages having open outer sides, said body being disposed axially in the mixing chamber.

2. The combination of a mixing chamber having an outlet at one end and an inlet for air at the opposite end and an inlet for vapor in one side, and a hollow open-ended body disposed axially in the mixing chamber with its receiving end presented to the air inlet of the chamber and having longitudinally disposed passages in its sides, all tapering throughout their length to gradually increase in capacity from the receiving toward the delivery end, some of the passages having open inner sides and the alternate passages 70 having open outer sides.

3. The combination of a mixing chamber having an outlet at one end, an inlet for air at the opposite end and an inlet for vapor in one side, and a mixer comprising a hollow open-ended body disposed axially in the mixing chamber with its receiving end presented to the air inlet of the chamber and having a centrally disposed baffle at the delivery end and provided in its sides with longitudinal 80 passages tapering throughout their length and having alternate open inner and outer sides.

4. The combination of a mixing chamber having an outlet at one end, an inlet for air at the opposite end and an inlet for vapor in one side, and a mixer comprising a hollow open-ended body disposed axially in the mixing chamber with its receiving end presented to the air inlet of the mixing chamber and having a centrally disposed baffle at the delivery end and provided in its side with longitudinal 90 passages tapering throughout their length and opening alternately inwardly and outwardly, the walls separating the passages being deflected laterally at their rear extremities in the same direction to impart a swirling movement to the air and mixture escaping from the respective passages to effect a 95 thorough mixing thereof.

5. The combination of a mixing chamber having an outlet at one end, an inlet for air at the opposite end and an inlet for vapor in one side, and a mixer disposed axially in the mixing chamber and comprising a hollow open-ended body of approximately conical form having its walls crimped or fluted to provide similar longitudinal passages which alternately open inwardly and outwardly and taper throughout their length in the same direction, and a centrally disposed baffle at the rear or delivery end of the mixer.

6. The combination of a mixing chamber having an outlet at one end, an inlet for air at the opposite end and an inlet for vapor in 120

- one side, and a mixer disposed axially in the mixing chamber and comprising a hollow open-ended body of approximately conical form and having its walls crimped or fluted
- 5 to provide similar longitudinal passages which alternately open inwardly and outwardly and taper throughout their length in the same direction, and a centrally disposed baffle at the rear or delivery end of the mixer,
- 10 the rear ends of the walls separating the passages being all deflected laterally in the same direction to impart a swirling movement to the air and mixture escaping from the passages.
- 15 7. The combination of a mixing chamber having an outlet at one end, an inlet for air in the opposite end and an inlet for vapor in one side and which is constricted at the outlet end, a mixer disposed axially within the
- 20 mixing chamber and comprising a hollow open-ended body formed with similar longitudinal passages in its side closed to each other and tapering throughout their length and alternately opening outwardly and in-
- 25 wardly, the delivery ends of the walls separating the passages being deflected laterally, and a baffle centrally disposed at the delivery end of the mixer to deflect the air outwardly and the constricted end of the mixing
- 30 chamber serving to direct the current of air and mixture inwardly across the ends of the respective passages.

In testimony whereof I affix my signature.
CHARLES E. BAILEY.
